(57) **CLAIM**

We claim the ornamental design for a liquid dispenser, substantially as shown and described.

DESCRIPTION

FIG. 1 is a perspective view of a liquid dispenser in a closed orientation in accordance with the present design;

FIG. 2 is a left side view of FIG. 1;

FIG. 3 is a right side view of FIG. 1;

FIG. 4 is a bottom view of FIG. 1;

FIG. 5 is a top view of FIG. 1;

FIG. 6 is a front view of FIG. 1;

FIG. 7 is a back view of FIG. 1;

FIG. 8 is a perspective view of a liquid dispenser in an open orientation in accordance with the present design;

FIG. 9 is a left side view of FIG. 8;

FIG. 10 is a right side view of FIG. 8;

FIG. 11 is a bottom view of FIG. 8;

FIG. 12 is a top view of FIG. 8;

FIG. 13 is a front view of FIG. 8; and,

FIG. 14 is a back view of FIG. 8.

The broken lines shown in FIGS. 1-3, 6, 8-10 and 13 illustrate portions of the liquid dispenser that form no part of the claimed design. The broken lines immediately adjacent to the claimed areas shown in FIGS. 1-5, 7-12 and 14 represent the boundaries of the liquid dispenser form no part of the claimed design.

1 Claim, 8 Drawing Sheets
